BEVERAGE DISPENSING MACHINE

Louis S. Wait, Beverly Hills, Calif., assignor of twenty-two and one-half per cent to Norman Bauch, fifteen per cent to David Robertson, nine and one-half per cent to Vincent Evans, nine and one-half per cent to Marjorie McDonald, one per cent to Oscar A. Tannenbaum, five per cent to G. W. Shelley, five per cent to Robert E. Shelley, and ten per cent to D. A. Rose, all of Los Angeles County, Calif.

Application July 26, 1954, Serial No. 31,618

Term of patent 3½ years

(Cl. D52—3)

Fig. 1

Fig. 3

Fig. 1 is a perspective view of a beverage dispensing machine, showing my new design;

Fig. 2 is a front elevational view thereof; and,

Fig. 3 is a side elevational view thereof.

The side of the beverage dispensing machine not shown is substantially like the side disclosed in the drawing.

I claim:

The ornamental design for a beverage dispensing machine, as shown and described.
